UNITED STATES PATENT OFFICE.

ARTHUR C. BAKER, OF OAK PARK, ILLINOIS.

COMPOUND RAIL.

1,258,976.

Specification of Letters Patent. Patented Mar. 12, 1918.

Application filed October 27, 1917. Serial No. 198,812.

To all whom it may concern:

Be it known that I, ARTHUR C. BAKER, a citizen of the United States of America, and a resident of Oak Park, county of Cook, and

5 State of Illinois, have invented certain new and useful Improvements in Compound Rails, of which the following is a specification.

This invention relates to compound rails, 10 and has as an object that the elements of the rail shall be arranged to exert a certain leverage upon each other for the purpose of making a rigid, noiseless structure not allowing for any relative movement between 15 the parts of the rail when the same are secured together.

Further objects of the invention are to provide improvements in compound rails permitting of their rapid assembly, and to 20 provide a removable tread which is normally locked with the base of the rail.

Figure 1 is a transverse section of an improved rail constructed according to this invention.

25 Fig. 2 is a sectional view illustrating the manner of assembling the parts of the rail.

Fig. 3 is a side view of the rail showing that the joints between the ends of the parts of the rail do not come in the same vertical 30 plane.

Some of the purposes of this invention are to enable the renewal of the tread portion of the rail without making necessary the unfastening of the rail flanges from the sleepers or bed of the railway; to dispense with fish-plates or other small fastening devices at the ends of the rails; to avoid irregular surfaces at the joints of the rails, and to provide a rigid noiseless structure.

40 The drawings illustrate the invention as applied to railway rails, and show a base 1 having the usual horizontal flanges 2 and the vertical web 3. The web 3 is formed at its upper end to provide a head 4 having the 45 flat bearing surface 5 upon which the cap or tread 6 of the rail rests. A third element, which may be of the same length as the tread and base members, or of less length, is shown as a lever 7 suitably formed to interlock with 50 the tread and base members, and also to bind or draw said members into firm relationship with each other.

For the latter purpose, the member 7 is provided with a convex surface 8 for coöperating as a cam with the concave surface 9 55 at one side of head 4 of the base. The mem-

ber 7 also has a longitudinal rib 10 for fitting within one of the channels 11 in the inner sides of depending flanges 12 of the cap 6. The flanges 12 are rolled inwardly 60 to correspond with the surface of rib 10 on the member 7, and a corresponding rib 13 formed at the side of head 4 which is opposite to its concave surface.

In assembling the rail, it will be understood that the base sections are first secured to the sleepers of the railway bed; then the tread portion 6 is hooked over the rib 13 of the head of the base member, and is swung around the rib 13 into the position in which 70 it is shown in Fig. 2; then the member 7 is inserted with the rib 10 foremost between the concave surface 9 and the remaining flange of the tread. The lower end of the member 7 is then forced toward the web 3, 75 drawing the tread downwardly toward the position in which it is shown in Fig. 1. The member 7 therefore acts as a lever, the fulcrums of which are between the rib 10 and one of the channels 11, and between the surfaces 8 and 9 of the lever and the base member respectively. The rib 13 of the base member serves as the fulcrum around which the tread is swung. Finally the entire structure is drawn taut by means of bolts 14 80 passed through apertures 15 and 16 in the web of base 3 and the lower end of lever 7. One or both sets of the apertures 15 and 16 may be slightly elongated to permit the circular motion of lever 7 around its fulcrums 90 when the nuts are screwed onto the bolts.

Although but one specific embodiment of this invention has been herein shown and described, it will be understood that numerous details of the construction shown may 95 be altered or omitted without departing from the spirit of this invention as defined by the following claims.

I claim:

1. A rail of the class described, comprising a base member, a tread member, and a tensioning member, said base and tread members being formed to afford a pivotal connection between each other at one side of the tread, said base and tensioning member 100 being formed to afford a pivoted connection between each other at the opposite side of the tread, and means for causing the tensioning member to draw the tread member 105 downwardly at its pivotal connection therewith.

2. A rail of the class described, compris-

ing a base member, a tread member, and a tensioning member, all of said members being of substantially uniform length and said tensioning member being in the form 5 of a lever having fulcrums on said base and said tread.

3. A rail of the class described, comprising a base member, a tread member, and a tensioning member, said base and tread

members being formed to afford a pivoted 10 connection between each other at one side of the tread, and said tensioning member being in the form of a lever having fulcrums at the opposite side of said tread and on said base member. 15

Signed at Chicago this 17th day of Oct., 1917.

ARTHUR C. BAKER.
